UNITED STATES PATENT OFFICE.

WELLS M. RUGGLES, OF MELLEN, WISCONSIN.

CROSSCUT-SAW CARRIER.

No. 915,384.

Specification of Letters Patent. Patented March 16, 1909.

Application filed September 28, 1908. Serial No. 455,136.

To all whom it may concern:

Be it known that I, WELLS M. RUGGLES, a citizen of the United States, residing at Mellen, in the county of Ashland and State of Wisconsin, have invented certain new and useful Improvements in Crosscut-Saw Carriers, of which the following is a specification.

This invention relates to a crosscut saw carrier.

10 One object of the invention is to provide a carrier for a cross cut saw embodying such characteristics that one man can operate the saw easier and more rapidly than can be done with the ordinary cross cut saw without the aid of my improved carrier.

15 Another object of the invention is to provide a carrier for cross cut saws constructed, arranged and associated with the saw in such a manner that the operator can instantly 20 adjust the feed of the saw.

Another object of the invention is to provide a device adapted to coöperate with the saw to hold up one end of the latter while it is in operation and at the same time to aid 25 the operator in pushing and pulling the saw backwardly and forwardly.

Another object of the invention resides in the provision of a carrier device of the nature stated embodying among other characteristics 30 a supporting means for the carrier constructed and arranged whereby it may be raised and lowered to suit the operation of the saw upon a log to be cut or in the event that it is desired to cut down a tree.

35 A still further object of the invention resides in the provision of a device of the nature stated embodying such characteristics that the carrier itself and its support may not only be adjustable but also foldable and the 40 device rendered portable.

With the above and other objects in view, the present invention consists in the combination and arrangement of parts herein-after more fully described, illustrated in the 45 accompanying drawings, and particularly pointed out in the appended claims, it being understood that changes may be made in the form, proportion, size and minor details without departing from the spirit or sacrificing 50 any of the advantages of the invention.

In the drawings:—Figure 1 is a side elevation of my invention in use for cutting a log in two. Fig. 2 is a top plan view, enlarged, of the head plate. Fig. 3 is a side view, enlarged, illustrating a portion of two of the 55 legs of the tripod, the head member, the pul-

ley and the carrier element. Fig. 4 is a detail view of one of the stirrup hooks. Fig. 5 is a side elevation of the invention illustrating its application when it is desired to cut 60 down a tree. Fig. 6 is a horizontal sectional view through the carrier.

Referring now more particularly to the accompanying drawings, the reference character 1 indicates a log disposed upon the 65 ground or any suitable support and if upon the ground checked in movement, if desired, especially if the log be disposed upon an incline, by means of a log or other suitable stop 2.

70 The character 3 indicates a cross cut saw of any variety provided with the usual handles 4. This saw, just alluded to, is used for sawing logs, cutting down trees, etc., and in its use it is usually necessary for the operator to continually hold up one end of the saw, usually that end provided with the handles 4. To obviate the necessity of holding up one end of the saw and for other reasons herein outlined, I provide a suitable 75 carrier for the saw which will not interfere with it in the performance of its usual functions.

The carrier device consists preferably of a 80 suitable support, preferably in the form of a tripod, including a head plate 5 provided with a series of spaced ears 6 between each pair of which is pivoted a member 7, the pivotal means consisting of a bolt 8. These 85 members 7 each include an eye 9 adapted to receive the upper ends of the corresponding legs, 10, 11 and 12, and by virtue of the pivot bolts 8, these legs may be drawn together or spread apart for the purpose of raising and lowering the head 5 of the support or tripod 90 to provide for an adjustment of the saw relative to the log.

Depending from the head 5 is a hook 13 upon which is disposed a pulley 14, over which latter works a helical spring 15 which 100 has an eye 16 formed at each end to receive the eyes 17 of the stirrup hooks 18, which latter are designed to embrace the end of the saw 3, the bills of the stirrup hooks being disposed upon opposite sides of the saw, as 105 shown.

It will be understood that my invention is not a sawing machine of itself but merely an attachment for the usual cross cut saw, and that it is nothing more nor less than an attachment in the form of a carrier adapted 110 particularly for use in connection with a

cross cut saw so that one man can operate the saw easier and faster than can be accomplished in the usual manual operation. It will also be understood that by spreading the 5 lower ends of the supporting legs toward and away from each other, that the carrier device or the spring may be adjusted accordingly. The device will readily coöperate with any variety of make of cross cut saws without 10 any change or alteration being made in the saw or in its mode of operation.

The operator takes hold of the handles on the saw and pushes and pulls the saw forwardly and backwardly across the object 15 being sawed in the same manner he does without the carrier. The carrier when used relieves the operator from having to hold up the end of the saw while it is in operation, while at the same time it aids the operator in 20 pushing and pulling the saw forwardly and backwardly. When the operator's arms are extended in pushing the saw forwardly or pulling it backwardly, that is, when they are at the end of the stroke in either direction, 25 the operator's arms are on a center, as it were. It is about midway of the stroke that the operator can and does exert the most power. The saw comes to a stop at the end of each stroke. If more power is expended 30 in pushing the saw forwardly to the end of the stroke than is required, it does not help the operator any in pulling the saw backwardly to the other end of the stroke. It is lost power unless there is something there 35 to take it up. The coiled spring performs this function, that is, it takes up power at each end of the stroke that would otherwise be lost, equalizing the power applied to the operation of the saw.

40 The spring is not attached to the saw with the object in view of holding the saw down on the log or other object that is being sawed, as is the case in sawing machines, but on the contrary the object of the spring in this case 45 is to lift up on the saw to a certain extent so that the operator can instantly adjust the feed of the saw by bearing down or "easing" up on the saw. The spring holds the saw up so that the feed thereof is but little unless the 50 operator bears down on it to some extent.

The object of having the spring double in form, that is, passed over the pulley 14 and connected at its opposite ends with the saw, is to render it more convenient to attach the 55 hooks to the saw and also to accomplish an equalization of the spring incident to its passage over the pulley. Moreover, the feed of the saw can be more quickly regulated in the use of my peculiarly arranged spring than in 60 the use of a straight, single spring, and it is obvious that the hooks may be attached to the saw close together or at different points apart to suit conditions.

Ordinarily a connection between the tripod 65 and the log is not necessary, because the

lower ends of the legs 10, 11 and 12 are preferably provided with spikes or picks 19 to enter the ground and thereby effect a firm mounting of the tripod. If desired, however, the legs of the tripod may each have a 70 staple 20 to slidably receive the helical springs 21, each provided at its free ends with the spikes 22 adapted to be driven in the ground and thereby insure against displacement of the carrier relative to the log. 75 However, these springs 21 will be seldom, if ever, used in the employment of my invention.

It may be desired to provide a connection 80 between the tripod and the log, and therefore, I provide each leg with a staple 23 through each of which latter may slidably work a helical or other flexible connection 24 provided at each end with a grappling hook 25 adapted to bite into the log 1. These 85 flexible connections 24 will permit of an adjustment of the carrier away from the log, if desired, without disconnecting the flexible connection either from the tripod or the log, and it will be understood that they are all independent one of another in that only one 90 will be used for connection with the log according to the position of the tripod.

In Figs. 5 and 6, it will be seen that one of the legs of the support or tripod, say for instance the leg 10, is lifted and secured against the side of the tree 26, by means of the corresponding flexible connection 24, the hooks of which latter would bite into or be driven into the tree, thereby securing the leg 10 firmly to 100 the tree and support the tripod upon its other legs. When the tripod is in this position, the stirrup hooks 18 engage opposite sides of the saw, which latter is disposed in a horizontal plane to cut down the tree, and the bills 105 of the stirrup hooks engage the back edge and the toothed edge of the saw, as shown. Thus the helical spring 15 in each use of the invention performs the same function.

What is claimed is:—

1. A carrier device for cross cut saws comprising a support including a head and legs, a pulley secured to the head, a spring suspended by said pulley, and hooks secured to the free ends of the spring to engage the saw. 110

2. The combination with a cross cut saw, of a carrier device comprising a support including a head and legs, a pulley secured to the head, a spring suspended from said pulley, and hooks secured to the free ends of the 115 spring, the hooks being arranged with their bills upon opposite sides of the saw.

3. A saw carrier device for cross cut saws comprising a support including a head and legs, a pulley secured to the head and suspended between the legs, and a helical spring bent back upon itself and suspended by said pulley, and hooks secured to the free ends of the 120 spring to engage the saw.

4. The combination with a cross cut saw, 125

of a carrier device comprising a support including a head and legs, a pulley secured to the head, a spring suspended from said pulley and slidable over the latter, and hooks secured to the free ends of the spring for engagement with the saw.

5. The combination with a cross cut saw, of a carrier device comprising a support including a head and legs, a pulley secured to the head, a spring suspended from said pulley and slidable over the latter, hooks secured to the free ends of the spring for engagement with the saw, and a flexible connection having engagement with each leg, 10 and a ground engaging element secured to each end of each flexible connection.

6. The combination with a cross cut saw and the log to be sawed, of a carrier device comprising a support including a head and 20 legs, a pulley secured to the head, a spring suspended from said pulley, hooks secured to the free ends of the spring for engagement with the saw, and a flexible connection between one of the legs of the support and the 25 log.

7. The combination with a cross cut saw and the log to be sawed, of a carrier device comprising a support including a head and legs, a pulley secured to the head, a spring 30 suspended from said pulley, hooks secured to the free ends of the spring for engagement with the saw, and a flexible connection slidable upon each leg for connection independently one of another with the log.

35. 8. The combination with a cross cut saw and the log to be sawed, of a carrier device comprising a support including a head and legs, a pulley secured to the head, a spring suspended from said pulley, hooks secured to the free ends of the spring for engagement 40 with the saw, a flexible connection slidable upon each leg for connection independently one of another with the log, and flexible connections engaging the legs independently of 45 the aforesaid flexible connection to anchor the legs to the ground.

9. A carrier device for cross cut saws comprising a supporting means, a helical spring slidably suspended from said supporting means, and means carried by said spring for engagement with the saw to exert a slight upward pull upon one end of the saw.

10. The combination with a cross cut saw and the log to be sawed, of a carrier device comprising a support including a head and 50 legs, a pulley secured to the head, a yieldable element suspended from said pulley and slidable over the latter, hooks secured to the free ends of the yieldable element for engagement with the saw, and ground engaging 55 means connected with said legs.

11. The combination with a cross cut saw and the log to be sawed, of a carrier device including a head, a pulley secured to the head, a yieldable element suspended from 60 said pulley, hooks secured to the free ends of the yieldable element for engagement with the saw, and means for connection between one of the legs of the support and the log.

12. A carrier device for cross cut saws 70 comprising a supporting means, a yieldable element slidably suspended from said supporting means, and means carried by said yieldable element for engagement with the saw to exert a slight forward pull upon one 75 end of the saw.

13. A carrier device for cross cut saws comprising a supporting means, a yieldable element slidably suspended from said supporting means, and hooks carried by said 80 yieldable element for engagement with the saw to exert a slight forward pull upon one end of the saw, said hooks being arranged with their bills for engagement upon opposite sides of the saw.

85 In testimony whereof I affix my signature, in presence of two witnesses.
